UNITED STATES PATENT OFFICE.

DENIS R. SULLIVAN, OF LONGVILLE, LOUISIANA.

REINFORCED-CONCRETE TIE.

1,384,496.

Specification of Letters Patent. Patented July 12, 1921.

Application filed November 17, 1920. Serial No. 424,726.

To all whom it may concern:

Be it known that I, DENIS R. SULLIVAN, a citizen of the United States, residing at Longville, in the parish of Beauregard and 5 State of Louisiana, have invented certain new and useful Improvements in Reinforced-Concrete Ties; and I do hereby declare the following to be a full, clear, and exact description of the invention, such as 10 will enable others skilled in the art to which it appertains to make and use the same.

This invention relates to a reinforced concrete tie, and the object is to provide, in a device of the character indicated, means including a heavy metallic plate adapted to 15 extend longitudinally of the tie and to be embedded therein, said plate having formed on the ends thereof upwardly extending rail engaging devices for contact with the outer 20 edges of the rail flanges, and the plate also carrying an element for receiving a threaded member engaging the inner edge of each flange.

A further object is to provide, in connection 25 with the foregoing structure, a reinforcement comprising a plurality of transverse elements mounted in a casing which in effect constitutes a mold, so that the metallic structure including the reinforcement *per se*, 30 the rail engaging devices, and the mold, are assembled in a complete manner at the beginning of the molding operation, and it is only necessary to pour in the plastic material and allow the latter to set, thereby producing 35 a reinforced concrete tie with a metallic casing, ready to be placed in position and secured to the rail by employing one threaded element for each rail for co-operation with the engaging devices previously 40 mentioned.

With the foregoing and other objects in view, the invention consists in the novel construction, combination and arrangement of elements hereinafter described and claimed, 45 it being understood that modifications or changes in construction may be made within the scope of the claims without departing from the spirit of the invention.

In the accompanying drawings: 50 Figure 1 is a view of the tie in vertical longitudinal section.

Fig. 2 is a top plan view.

Fig. 3 is a detail in perspective of the 55 central horizontal plate, constituting an element of the reinforcement, and serving to directly mount the rail engaging devices.

Fig. 4 is a view in vertical transverse section.

Fig. 5 is a detail of construction described 60 below.

Fig. 6 is a detail perspective view of one of the plates upon which the rails seat.

In carrying out my invention, I provide the casing or form, including the bottom wall 10, the side walls 12 and 13, and the end 65 walls 14 and 15. The end walls may overlap the bottom and side walls, being provided with flanges 16, as shown.

Extending transversely between the side walls, are braces 18 having offset ends 19, 70 these elements being secured to the side walls by means of rivets or bolts 20. Bolts would be employed in the event that the casing or form is made of wood.

The transverse braces may be arranged in 75 any suitable manner, but in the drawings I have shown them arranged in pairs, the two braces of each pair being in substantially vertical alignment.

The heavy metallic plate 22 is located 80 above the lower braces of the respective pairs, and below the upper braces, or tie members. Formed on the ends of this plate are the rail engaging devices 23, one of the latter being located near each corner. The 85 elements 23 of the form of the spike each include a shank portion, and a head 24, for engaging the outer edge of the rail flange.

When the cement, constituting the body of the tie, is poured into the form, or prior to 90 that operation, the plate 22 is lifted to an upper position, and into approximate contact with the upper braces. When the form is nearly full of the plastic material, the plate is released, and dropping by gravity 95 has the effect of tamping the cement.

In the form shown in Fig. 5, this being a fragmentary view, a rubber cushion 25 is placed beneath the pipe 22, this construction meeting the requirements of a resilient tie, 100 in the event that provision for resiliency is considered necessary.

A plurality of tubular elements 26 are mounted in a vertical position on plate 22 and are provided at their upper ends with internally threaded portions 27, adapted for engagement by the threaded shank of a bolt 28, for securing in position the plates 29, directly engaging the inner edge of the rail flange, at a point between the rail engaging 110 devices previously mentioned. Split spring washers 30, serve the usual purpose.

The rails, sections of which are shown in the drawings, and are designated 31, are mounted respectively on transverse plates 32 and 33, each provided with flanged portions 34, on opposite edges, for engaging the upper portions of the side walls of the form.

Each plate is notched, as shown at 35 and 36, for coöperation with the rail engaging devices 29, and each plate is further provided with an aperture 36 through which the elements 26 project.

What is claimed is:—

1. In a device of the class described, a body portion, reinforcing devices extending therethrough, and an additional reinforcing device including rail supporting elements, and comprising a plate embedded within the body, and rail engaging devices projecting upwardly from the ends of the plate, for engagement with the outer portions of the rail flanges, and means carried by said plate for securing the inner edge portions of the rail flanges.

2. In a device of the class described, a body portion reinforcing means embedded therein, additional reinforcing means serving as rail engaging devices, said means last mentioned comprising a plate extending longitudinally of the body, elements projecting upwardly from the ends of said plate and headed for engagement with the rail flanges, threaded members carried by said plates, and projecting upwardly therefrom, in alignment with the inner edges of the rail flanges, an element engaging the rail flange, on the inner side thereof, and means for securing said elements to those elements mounted in alignment with the inner portions of the flanges.

3. In a device of the class described, a form including a bottom, sides, and ends, devices connecting the sides at intervals, plates connecting the upper portions of the sides and serving to mount the rails of a track, and securing means for said rails, the securing means comprising an element to be embedded in the tie to be molded in the form and de-

vices projecting upwardly from said elements, in spaced relation, for engagement with the rail flanges, on opposite sides 50 thereof.

4. In a device of the class described, a form comprising a bottom, side walls, and end walls, devices connecting the side walls at intervals, a body of plastic material with 55 in said form and reinforced by said connecting devices, and rail mounting and securing means comprising a plate embedded in the body portion, and elements mounted on said plate and projecting upwardly through the 60 body, for engagement with the rail flanges on opposite sides thereof.

5. In a device of the class described, a form comprising a receptacle approximately rectangular in cross section having its upper portion open, a body of concrete or the like within said form, rail engaging and securing means embedded in the body portion and including devices projecting upwardly therefrom, plates connecting the upper edge 70 portions of the form, said plates having openings therein for coöperation with the upwardly projecting devices, and a plate bearing on the upper surface of the body portion and serving to directly mount the 75 rails to be retained by the aforesaid securing devices.

6. A rail securing device for a concrete tie, comprising a plate to be embedded within the tie, upwardly projecting elements connected with the ends of said plate and provided with heads for engaging the rail flanges, upwardly projecting elements carried by the plate in approximate alignment with the inner edges of the flanges of the 85 rails, devices engaging the inner edges of the flanges, and bolts for securing said devices to the projecting elements last named.

In testimony whereof I affix my signature in presence of two witnesses.

DENIS R. SULLIVAN
